UNITED STATES PATENT OFFICE

145,443

DESIGN FOR A COMBINATION CHAIR AND TABLE

Louis S. Harsany, Cleveland, Ohio

Application November 29, 1945, Serial No. 124,183

Term of patent 14 years

(Cl. D33—11)

To all whom it may concern:

Be it known that I, Louis S. Harsany, a citizen of the United States, residing at Cleveland, in the county of Cuyahoga and State of Ohio, have invented a new, original, and ornamental Design for a Combination Chair and Table, of which the following is a specification, reference being had to the accompanying drawing, forming a part thereof, in which:

Fig. 1 is a perspective view of a combination chair and table embodying my new design.

Fig. 2 is a top plan view of the combination chair and table;

Fig. 3 is a front elevational view thereof; and
Fig. 4 is a fragmentary elevational view showing the lower portion of the remote side of the device as seen in Fig. 1.

I claim:

The ornamental design for a combination chair and table, substantially as shown.

LOUIS S. HARSANY.
